DESIGN FOR A SEWING MACHINE FRAME

Norman Wonnacott, Scarsdale, N. Y., assignor to
Willcox & Gibbs Sewing Machine Company,
New York, N. Y., a corporation of New York

Application May 8, 1940, Serial No. 92,212

Term of patent 14 years

To all whom it may concern:

Be it known that I, Norman Wonnacott, a citizen of the United States, residing at Scarsdale, in the county of Westchester and State of New York, have invented a new, original, and ornamental Design for a Sewing Machine Frame, of which the following is a specification, reference being had to the accompanying drawings, forming a part thereof, and in which—

Figure 1 is a perspective view of the sewing machine frame showing my new design.

Fig. 2 is a top plan view;

Fig. 3 is a side elevational view; and

Fig. 4 is an end elevational view thereof.

I claim:

The ornamental design for a sewing machine frame, substantially as shown.

NORMAN WONNACOTT.
